UNITED STATES PATENT OFFICE.

MARIE AMÉLIE BALTHASAR, OF NAMUR, BELGIUM.

PNEUMATICALLY-OPERATING MUSICAL INSTRUMENT.

Application filed June 3, 1922. Serial No. 565,612.

To all whom it may concern:

Be it known that I, MARIE AMÉLIE BALTHASAR, subject of the King of Belgium, and resident of Namur, Belgium, have invented 60
5 certain new and useful Improvements in Pneumatically-Operating Musical Instruments, of which the following is a specification.

This invention relates to pneumatically 10 operating musical instruments with deadened vibrations.

In instruments of this type, the hammers adapted to strike the strings or other sound generators are actuated by bellows, the inner chamber of which can be connected either with the atmosphere, or with a pipe line in which exists a reduced pressure. In the first case, the bellows remains stationary, in the second case, the bellows is actuated 20 and the string corresponding to this bellows is caused to vibrate.

The primary control member of the pipe line leading to the bellows is a perforated paper strip which unwinds in front of the 25 orifices of the pipe lines, for obturating them or connecting them with the atmosphere. As the pipe lines have a branch of small diameter connected to the reduced pressure chamber, it will be seen that when the orifice 30 of a pipe line is closed by the paper strip, a reduced pressure is determined in this pipe line, and on the contrary, when the pipe line is opened, it is immediately brought back to atmospheric pressure.

It will be understood that it is impossible 35 to directly control the bellows by the perforated paper strip, as the perforations would be too long, the notes being at rest when their bellows communicate with the atmosphere.

Reversing relays are therefor used, which allow the bellows to communicate with the atmosphere when the orifices controlled by the paper strip are closed.

These relays are each constituted by a 45 valve moving between two seats, one of which opens to the atmosphere the other to the reduced pressure chamber, and which controls the pipe line of the bellows. The 50 valve which when at rest connects the bellows with the atmosphere, is actuated by a resilient diaphragm, on one of the faces of which permanently acts the reduced pressure and which closes, by its other face, a chamber connected with the atmosphere by a pipe line controlled by the perforated pa-

per strip. This chamber is, moreover, perforated with a hole of small diameter which connects it to the pipe line in which exists a reduced pressure. 65

It will be understood that the valve is actuated and consequently the bellows corresponding thereto, only when a hole is presented in front of the orifice controlled by the paper strip. 70

The conditions for the proper operation of the said reversing relays are the following:

1°—The valve, when it is actuated, must immediately leave the seat on which it rests 75 (seat open to the reduced pressure).

2°—It must pass from one seat to the other, with the maximum possible speed.

3°—When the diaphragm ceases to act, the valve also must immediately come back to 75 rest.

The invention has essentially for its purpose to realize these conditions. It is also adapted to permit the ready adjustment of the distance between the two valve seats 80 and, also, to allow the adjustment of the distance separating the resilient diaphragm and the valve, without necessitating taking the relay to pieces.

The invention is described hereinafter 85 with reference to the accompanying drawing which diagrammatically illustrates, by way of example, a form of construction.

Fig. 1 is a partial sectional elevation.

Fig. 2 is a view similar to Fig. 1, the 90 valve being in a different position.

Fig. 3 is a plan view.

Fig. 4 is a sectional view on line A—A of Fig. 2.

In this example, 1 designates a striker arm, and 2 a movable wall of a bellows, the inner chamber 3 of which is connected by the pipe 4 to the chamber 5 having two valve seats, one of which 6, opens to the atmosphere, and the other of which, 7, in the chamber 8 is tubular, and is connected by the pipe 9 to a reduced pressure generator. The valve 10 can seat on one or the other of the seats, and when at rest, it fits on the seat 7. Its pilot 11, guided by tubular seat 7, rests on the resilient diaphragm 12 closing the box 13 perforated with a small hole 14 and connected to the pipe 15 controlled by the perforated paper strip 16. 95 100 105

Further, the chambers 5 and 8 are formed 110 by two metallic boxes 17 and 18 assembled in a fluid-tight manner on the intermediate

metallic partition 19. Moreover, the seat 7 is constituted by a cylindrical tube capable of frictionally sliding in a corresponding orifice of the partition 19, and the stroke of the valve 10 can therefore be modified by means of the sliding movement of the tube 7.

Besides the pilot 11, which has a polygonal cross section (square cross section in the example illustrated,) is guided in the 10 tube F. Consequently, when the valve is moved away from its seat F, a communication is established between the chambers 8 and 5 (Figure 3) through the space existing between the polygonal periphery of the 15 pilot 11 and the inner cylindrical surface of the tube F.

Also, the box 13 carries a branch 20 capable of frictionally sliding in the tube 21 integral with the box 18, which branch extends 20 to the exterior of the box 18.

By acting on the branch 20, the box 13 can therefore be moved towards or from the pilot 11 without removing the element. The operation is as follows:

25 The valve 10 is supposed to rest initially on the seat 7 and the pipe 15 to be closed by the perforated paper strip 16.

Phase 1.—The valve 10 resting on the seat 7, the bellows 3 communicates with the 30 atmosphere and the parts occupy the position illustrated in Fig. 1.

A partial vacuum exists in both the chambers 8 and 13, owing to the blow-through hole 14 (called "capillary hole" because of 35 its small diameter) and for the reason that the pipe 15 is obturated by the perforated paper strip 16.

Phase 2.—A hole of the perforated paper strip 16 comes in coincidence with the orifice 40 of the pipe 15. The air then enters in this pipe and produces the following results:

1°—Owing to its speed and by reason of its kinetic energy (living force) the quantity of air introduced lifts the diaphragm 45 12 and consequently produces the immediate unloosening of the valve 10 from its seat.

2°—The chamber 13 comes under a pressure close to that of atmospheric pressure and in any case greater than the pressure 50 existing in 8. Consequently, the diaphragm 12 continues its action on the pilot 11, of the valve 10 until the latter rests on the seat 6.

In consequence, the bellows 3 is put into 55 communication with a partial vacuum, and the movable partition 2 folds back on the fixed partition, drawing along the striker arm 1.

Phase 3.—The perforated paper strip 60 again obturates the pipe 15. Owing to the hole 14 a partial vacuum is created in the chamber 13 and the diaphragm 12 becomes inert. In consequence, the atmospheric pressure which is exerted on the upper face 65 of the valve 10 determines the displacement

of this valve which closes on the seat 7. The bellows 3 is again connected with the atmosphere and all the members again assume the position illustrated in Fig. 1.

It has been indicated that the conditions 70 for the proper operation of the system are the following:

1°—Instantaneous loosening of the valve 10 from its lower seat 7.

2°—Maximum speed of application of the 75 valve to its outer seat 6.

3°—Instantaneous return of the valve to the lower seat 7.

Condition I—It has been previously noted that the kinetic energy (living force) of the 80 air suffices to produce the loosening of the valve from its lower seat 7 which would take place even if there was no difference between the surface of the diaphragm 12 and that of the seat 7.

Condition II—On the other hand, if S^{12} is the surface of the diaphragm 12, s^6 the surface of the seat 6, H the atmospheric pressure, h the pressure in the vacuum pipe line, then the force which tends to apply the 90 valve to the seat 6 is, $(H-h)(S^{12}-s^6)$. It is therefore obvious that S^{12} must be as great and s^6 as small as possible, without however the outflow of the seat 6 being diminished.

For this reason, the seat 6 is composed of 95 several holes surrounded by conduits turned towards the valve 10, as clearly illustrated in the drawing. The outflow can thus be maintained equal to, or greater than, the outflow of the single hole generally used in 100 apparatuses of this kind, and the total surface of the multiple holes is less than that of the single hole. In fact, the outflow depends on the perimeter of the openings, admitting that the lift of the valve and the value of 105 the partial vacuum remain constant. Now the perimeter of the sum of the multiple holes, in case they are five in number, as in the example illustrated, is equal to $10\pi r$, r being the radius of each of the holes. The 110 perimeter of the single hole having R for radius and giving the same outflow as the multiple holes would be.

$$2\pi R = 10\pi r$$

thus giving:

$$r = \frac{R}{5}$$

It is then seen that the total surface of 120 the multiple holes is:

$$5\pi r^2 = \frac{5\pi R^2}{25} = \frac{\pi R^2}{5}$$

that is to say the fifth of the surface of the single hole having the same outflow.

125 It is to be noted that it is indispensable that the multiple holes should be surrounded by conduits, because it is necessary that the section of passage of the air between two successive holes should be sufficiently great 130

for permitting the outflow of multiple holes, and the existence of conduits increases the height of this section of passage of the air, which allows placing the holes nearer together and, consequently, diminishing the space occupied.

Condition III—The force which produces the return of the valve is obviously so much the greater according as the surface subjected to the partial vacuum is also greater. It is for that reason that the seat 7 is a seat having a single hole, and consequently presenting a large surface. Apparatuses already exist in which the seat opening to the atmosphere has a large outflow and a small surface, but the seat opening to the partial vacuum also has a large outflow and a small surface, so that this condition III is not realized in the said apparatuses.

20 The invention is characterized on the contrary by the combination of an upper seat having multiple holes and flanged edges (consequently having a small surface although a large outflow), with a lower seat 25 having a single hole (consequently having a large surface).

What I claim as my invention and desire to secure by Letters Patent is:

1. In a pneumatically operating musical 30 instrument, a metal plate forming a valve seat, a plurality of apertures, with flanged edges provided on the said seat, a valve, a valve stem, a tube forming a guide from the said stem and forming at the same time a second valve seat having a single aperture, a plate for supporting the said tube, means for moving the tube relatively to the said plate, a diaphragm acting on the valve stem, a diaphragm chamber, an axial tube forming an

extension of the said chamber, and means 40 for supporting the axial tube.

2. In a pneumatically operating musical instrument, a metal plate forming a valve seat, a plurality of apertures with flanged edges provided on the said seat, a valve, a 45 valve stem, a tube forming a guide for the said stem and forming at the same time a second valve seat having a single aperture, a plate for supporting the said tube, means for moving the tube relatively to the said 50 plate, a diaphragm acting on the valve stem, a diaphragm chamber, an axial tube forming an extension of the said chamber, a plate for supporting the axial tube, and means for moving the latter relatively to this plate. 55

3. In a pneumatically operating musical instrument, a casing, a plurality of apertures with flanged edges provided in the bottom of this casing, a second casing fitting the first one, a central aperture in this second casing, a valve, a valve stem, a tube forming a guide for the said stem and forming at the same time a second valve seat having a single opening, the valve stem passing through the said single opening, a third casing 60 covering the second one, an aperture in this third casing, a diaphragm, a diaphragm chamber, a tube forming an extension of this chamber and passing through the aperture provided at this chamber and passing 70 through the aperture provided at the bottom of the third casing, a side pipe entering the first casing, and a side pipe entering the third casing. 65

Signed at Brussels, Belgium, this twenty- 75 second day of May A. D. 1922.

MARIE AMÉLIE BALTHASAR.
